CANDLE ILLUMINATED TOY OR ORNAMENT

Barry Murphy, Palo Alto, Calif.

Application October 27, 1948, Serial No. 56,770

4 Claims. (Cl. 67-27)

1

This invention relates particularly to Christmas and holiday toys and ornaments as used for decorating about the Christmas tree and other places in the vicinity and home.

The principal object of the invention is to provide a means for self contained candle illumination for such objects without making the objects themselves of tallow provided with a wick, and for obtaining a constant safe candle flame illumination without the danger of fire usually attendant with the use of candles at festive occasions.

Other objects and advantages of the invention will appear in the following description and accompanying drawings.

In the drawings:

Figs. 1 to 5 inclusive show various holiday ornaments or decorative toys to which my improvement has been applied, the devices being respectively a Santa Claus standing figure, the head of a person, a toy house, an egg, and a pig.

Fig. 6 is an enlarged vertical cross section of the candle mounting of Fig. 1 as taken parallel to the plane of the drawing sheet.

Before describing the drawings in detail it will give a better understanding of the invention to mention the fact that in holiday decorations, especially at Christmas time, the use of naked candles is historic, so is the number of fires occurring therefrom, as the candles melt and the grease catches fire to spread the flames. Besides regular candles, it has in recent years become the custom to manufacture decorative candles in various forms other than plain shafts, thus a whole image as of a saint will be molded of tallow with the wick projecting at the top of the head, or a round thick body of tallow in the form of an orange with the wick projecting at the top, as respectively shown in design patents Des. 119,498 and Des. 115,947. Also last Christmas season, very large blocks of tallow or paraffin appeared on the market in the form of a translucent head of Santa Claus as a mantle ornament with a rear portion having a projecting wick to cast a light through the forward portion, and the whole article being of tallow or paraffin could lead to a disastrous fire as the burning wick melted it down.

My invention, therefore, has as one of its objects the production of such holiday ornaments or festive figure of a fireproof substance such as plaster of Paris, clay, or any of the non-inflammable plastics, opaque or translucent, or of glass, and which will carry within them one or more concealed candles with only the flame extending

2

upward therefrom and with nothing inflammable within its reach.

In the drawings, the various views 1 to 5 indicate three dimensional ornamental holiday figures, the body portions of which, respectively A, B, C, D, and E are of non-combustible material, preferably moulded, pressed, or otherwise formed and designed to be self-sustaining and to stand firmly on a mantle or other support, although if to be used as a tree decoration they may be of any other form for suspension or otherwise attaching to the tree.

Within the body or substance of the material S of which the image is formed is a vertical cylindrical bore 7 reduced at its upper end to a smaller opening, and entering at its lower end a much larger counter bore or cavity 9 preferably open at the bottom for accessibility of a sheet metal or other non-combustible sheet material tube or sheath 10 tightly fitting within bore 7 and extending down into the larger cavity 9 below where it is preferably closed as by a lid 11 which telescopes over the lower end of the tube and fastens by a fractional turn as by a bayonet joint 12, and which provides for inserting or renewing the candle.

The upper end of tube 10 is reduced in diameter, as at 13 and preferably conical to stop against the similarly reduced upper end 8 of the bore 7, and forms a centering stop for the candle, while within the tube 7 is a freely slideable candle 17 urged upward by a coiled spring 14 so that as it is melted by its flame 15 from its burning wick 16 the candle will always be correspondingly forced upward against the conical stop 13. It is obvious that the sheath 7 may be formed integral with and of the body material if desired.

Such spring urged candles in a tube are in themselves not new, but have been known a long time, but in so far as I am aware they have been spring urged candle sticks merely, even though sometimes of elaborate shape, but not such a device bodily mounted in non-combustible holiday ornaments as herein described and which is an important improvement tending to greatly reduce the fire hazard of candle illumination on Christmas and other festive occasions, and in which improvement the candle flames appear to burn directly upon the upper surface of the illuminated article.

From a consideration of the disclosure, and the drawings under A, B, C, D, and E showing respectively a Santa Claus, head of a person, house, egg, and a pig, it is obvious that no limit as to the ornamental form of the body is intended.

as it may embrace all animals, fowl, birds, or in fact everything imaginable that finds use as a Christmas or holiday ornament, and all such items are intended to be included in the group named. I therefore claim:

1. A holiday ornament comprising a three dimensional bodied figure formed of non-combustible material and a candle embedded in a vertical bore therein with the upper end of the candle adjacent an upper surface of the figure to bring its flame when lighted just above the adjacent upper surface of the figure, spring means automatically urging said candle upwards, a stop fixed relative to the body at the extreme end of the bore overlapping and limiting the upward movement of said candle, and an enlarged cavity in said body below said candle freely open at its lower end to permit removal of said candle downwardly through said cavity.

2. A holiday ornament comprising a three dimensional bodied figure formed of non-combustible material and a candle embedded in a vertical bore therein with the upper end of the candle adjacent an upper surface of the figure to bring its flame when lighted just above the adjacent upper surface of the figure, spring means automatically so maintaining said candle as it is consumed, a sheath surrounding said candle and in which it is freely slideable, and an enlarged cavity in the body of said figure below said sheath opening outwardly of the body and into which cavity the sheath extends, and means making said candle accessible to the fingers of a hand through said cavity.

3. In a Christmas toy type ornament, a three dimensional body formed of non-combustible material with a concealed candle embedded in said body and vented for lighting at an upper surface

of said body, spring means urging said candle upward to bring its flame just above the body, and a lower cavity formed in the body below said candle opening downward of the body and through which cavity the candle is accessible for manual insertion and removal.

4. A holiday ornament comprising a three dimensional bodied figure of non-combustible material, a vertical bore in said figure with a restricted upper end open at the upper surface of said figure and terminating at its lower end in an enlarged open cavity at the bottom of the figure, a tube secured in the vertical bore with its top end portion abutting the restricted portion of the bore and its bottom end portion projecting into the enlarged open cavity, a concealed candle in the tube, a lid releasably retained on the bottom end portion of the tube in said enlarged open cavity, and a coil spring supported in the tube by said lid to urge the concealed candle upwardly and project its wick through the upper restricted opening in said three dimensional bodied figure.
